(57) **CLAIM**

The ornamental design for a display screen or portion thereof with a graphical user interface of an electronic device, as shown and described.

DESCRIPTION

This application claims priority to U.S. Provisional Patent Application No. 62/362,821 filed on Jul. 15, 2016, entitled “GROUP MATCHING SYSTEM AND METHOD,” the disclosure of which is hereby incorporated by reference. FIG. 1 is a front view of a first embodiment of a display screen with a graphical user interface of an electronic device.

FIG. 2 is a front view of a second embodiment of a display screen with a graphical user interface of an electronic device.

FIG. 3 is a front view of a third embodiment of a display screen with a graphical user interface of an electronic device; and,

FIG. 4 is a front view of a fourth embodiment of a display screen with a graphical user interface of an electronic device.

The broken lines showing a display screen or portion thereof with a graphical user interface of an electronic device illustrate portions of the article, and form no part of the claimed design.
